UNITED STATES PATENT OFFICE.

NEWTON K. BOWMAN, OF LAWRENCE, OHIO, ASSIGNOR TO ALVIN HURFORD, OF CANTON, OHIO.

MINE-GATE.

SPECIFICATION forming part of Letters Patent No. 613,751, dated November 8, 1898.

Application filed February 18, 1898. Serial No. 670,813. (No model.)

To all whom it may concern:

Be it known that I, NEWTON K. BOWMAN, a citizen of the United States, residing at North Lawrence, in the county of Stark and 5 State of Ohio, have invented new and useful Improvements in Mine-Gates, of which the following is a specification.

My invention relates to improvements in mine-gates of the class shown and described 10 in my application for Letters Patent of the United States, filed November 20, 1897, Serial No. 659,311, in which a folding gate-curtain operated to open and close the mine-passage by coacting depressible platforms is provided.

15 The object of this invention is to provide a novel form of gate and simple and effective operating mechanism therefor adapted to be actuated to open the gate by the wheels of a car running along the track-rails.

20 To this end the invention consists in certain novel features of construction, combination, and arrangement of parts, as will be herein-after more fully described, and particularly pointed out in the appended claims.

25 In the accompanying drawings, forming part of this specification, Figure 1 is a perspective view of a mine-gate embodying my invention. Fig. 2 is an end elevational view of same. Fig. 3 is a front elevational view 30 of portion of the gate and coöperating parts. Fig. 4 is a detail perspective view of portion of the gate and one of the posts, showing the arrangement of the cord and pulley. Fig. 5 is a similar view, a portion of the post being 35 broken away to show the guide-groove. Fig. 6 is a detail cross-sectional view showing the gate-curtain folded.

Like letters of reference designate corresponding parts throughout the several views.

40 A represents the gate-curtain arranged transversely of the track-rails B B' and C C', the gate-posts connected at their upper ends by a cross-bar D. The curtain is made of some suitable waterproof material, preferably 45 canvas or ducking, and is made fast at its upper end to the cross-bar D and secured at its lower end to a counterweight-bar E, which is adapted to close the curtain by gravity. The ends of this bar E are fitted to slide in ver- 50 tical guide-grooves f, formed in the inner sides of the posts.

The curtain is stiffened to resist air-pressure by transverse battens or slats g, provided at the ends thereof with eyes g', through which loosely extend the operating-cords h h', which 55 pass over grooved pulleys i i' on the posts and connect the opposite ends of the bar E with the free ends of the operating-levers K K'. The transverse battens are secured to the curtain at suitable distances apart in such manner that the flexible portions of the curtain between adjoining battens serve as hinges to permit said battens to successively assume a horizontal position and lap against one another in folding the curtain, as shown in Fig. 60 65. When folded, the battens lie closely in contact between the bars D E. This operation takes place when the cords are drawn upon by the outward movement of the levers K K', as will be readily understood. 70

The construction of parts thus far described is substantially the same as that shown and claimed in my allowed application hereinbefore mentioned and, broadly considered, forms no part of my present invention. 75

The specific improvements to which this invention relates will now be described.

The levers K K' are provided at their lower ends with crank-arms k and are pivotally connected adjacent thereto to the opposite 80 ends of one of the cross-ties L. Arranged on the outer sides of the track-rails B B' and extending parallel therewith are depressible bars M M', which are connected by means of arms o o' to rock-shafts P P', mounted to 85 oscillate in bearings q q' on the projecting ends of the ties. The depressible bars are connected to the crank-arms of the levers by connecting-rods p p' and links s s', the construction being such that when the bars are 90 depressed the crank-arms on the lower ends of the levers will be thrown upward and the upper ends of said levers outward, as represented by broken lines in Fig. 2. The connecting-arms o' at the ends of the depressible bars may be provided with inclined extensions l, carrying adjustable counterweights o³, which serve to return the rock-shafts to their normal position and hold the depressible bars elevated. 95

100 The operation of the gate is as follows: When a car running on the rails nears the

gate, its wheels depress the bars M M' and 5 tilt the rock-shaft, causing the outer ends of the pivoted connecting-rods p p' to swing upward and carry with them the crank-arms k , thereby moving the upper free ends of the 10 levers outward to the dotted-line position shown in Fig. 2. The cords h h' being secured to the levers will move in accordance therewith and raise the lower end of the curtain, causing it to fold in the manner shown 15 in Fig. 6 and open the gateway. The gate-curtain will remain open until the car passes over the compressible bars, whereupon the gate will be caused to unfold and close the 20 gateway by the weight of the bar E , and at the same time the compressible bars and coacting parts will be restored to their normal positions through the combined action of bar E and the counterweights o^3 , as will be readily 25 understood.

I desire it understood that changes in the form, proportion, and minor details of construction may be made within the scope of the invention without departing from the 30 spirit or sacrificing any of the advantages thereof.

Having thus fully described my invention, what I claim as new and useful, and desire to 35 secure by Letters Patent, is—

30 1. In a mine-gate, the combination with the track-rails, of rock-shafts mounted on the ties thereof, compressible bars extending parallel with the rails and connected with said shafts, a folding gate-curtain, operating-levers piv-

35 oted to one of the ties and provided at their lower ends with crank-arms, connections between the compressible bars and crank-arms of the levers, and operating-cords connecting the curtain with the upper ends of the levers, 40 substantially as described.

2. In a mine-gate, the combination with the track-rails, of gate-posts provided on their

inner faces with grooves and carrying pulleys at their upper ends, a folding gate-curtain made fast at its upper end and provided 45 at its lower end with a gravity-bar arranged to traverse said grooves, a series of transverse battens on the curtain provided at their outer ends with eyes, cords connected with the projecting ends of the gravity-bar and 50 extending through the eyes of the battens and around said pulleys, rock-shafts mounted in bearings on the projecting ends of the rail-ties, compressible bars extending parallel with the rails and secured to said shafts, each of 55 said bars being provided with a laterally-projecting connecting-arm, operating-levers provided at their lower ends with crank-arms and pivoted adjacent thereto to the ends of one of the rail-ties and connected at their 60 upper ends to the said operating-cords, and links connecting the crank-arms of the levers with the said laterally-projecting arms of the compressible bars, substantially as described.

3. In a mine-gate, the combination, with the 65 track-rails, of a compressible bar, extending parallel with said rails, a folding gate-curtain provided with a series of transverse battens and a weighted bar at the lower end thereof, levers operatively connected with 70 said compressible bars, and cords connecting the weighted bar on the lower end of the curtain with said levers, whereby the downward movement of the compressible bars will cause the curtain to fold, substantially as de- 75 scribed.

In testimony whereof I have hereunto set my hand in the presence of two subscribing witnesses.

NEWTON K. BOWMAN.
